PRUNING DEVICE

Friedrich May, Magdeburg, Germany

Application December 10, 1934, Serial No. 756,762
In Germany August 30, 1933

4 Claims. (Cl. 30—11)

This invention relates to a device for pruning branches by means of knives connected with one another and operated by the intermediary of levers subjected in one direction to the action of springs by means of which they are moved back, together with the knives, into their position of rest. My present improved pruning device is distinguished from the known devices for the purpose in view by the characterizing features that one of the two flat knives, or knife blades respectively, forming parts of the implement and being shiftable relatively to one another is coupled with a one-armed lever, whereas the other blade is coupled with a double-armed lever, preferably in such a manner that the blades can be adjusted at said levers.

Designing the pruning device in this manner renders it possible to manufacture it on the whole-sale scale at a low price, and further advantages are that this improved device is very reliable in service and operates unobjectionably and without jamming even if the blades are not held exactly at right angles with respect to the branches to be lopped-off.

In a preferred constructional form of this device the two levers mentioned are connected with one another by a serrated bar, or a saw blade respectively, may be in connection with a spring-actuated member able to take up the recoils.

The invention is illustrated diagrammatically and by way of example on the accompanying drawing which shows a side-view of a pruning device designed according to this invention.

On the drawing, 1 and 2 are the two knife blades which are arranged above one another and of which 1 is shiftable between guide members 3 and 4 forming parts of a rigid frame 5, whereas the blade 2 is shiftable between said guide member and a guide member 7 having a guide groove 6 and being preferably detachably attached to said frame 5. The blade 1 is coupled with a one-armed lever 12 fulcrumed at 11 to the guide member 3. In said lever is a slot 10 and in said blade is a slot 8, and a bolt 9 though both slots can be adjusted in the slot 8 and secured therein after the adjustment. The bolt slides in the slot 10 when the lever 12 is moved up and down in order to actuate the blade 1. Likewise the blade 2 is coupled with a double-armed lever 17 fulcrumed at 16 to the frame 5; it has a slot 13 and said lever has a slot 15, and a bolt 14 extends through both these slots. The bolt 14 can be adjusted and fixed in its adjusted position in the same manner as the bolt 9 which will be clear without a more detailed explanation.

The two blades can be moved simultaneously, counter to one another, by means of a rope 20 or the like. In the preferred constructional form shown by way of example, the rope 20 terminates already at the lever 17 and the connection be-

tween this lever and the lever 12 is effected by means of a saw-blade 18 so that the implement can be used also for sawing purposes.

Drawing the levers back into their position of rest can be effected, for instance, either by means of a helical tensile spring 21 engaging the lever 12 or by means of a helical tensile spring 22 engaging the lever 17 or by both these springs, as in the drawing. It is suited to the sawing purpose to insert between the blade 18 and the lever 12 a recoil device 19, as in the figure shown.

23 and 24 are abutment members for the two levers, and 27 is a wooden rod, to the upper end of which the implement is attached. The lower portion of this latter is tubular, as at 26, and 15 receives in it the correspondingly shaped upper end of said rod. Below the guide member 7 the frame 5 is provided with a hook 25 serving for tearing down branches that have not been completely severed off by the knife blades. 20

I claim:

1. A branch pruning device, comprising, in combination, two oppositely located knife blades movable in opposite directions, means guiding said blades, a one-armed lever coupled with one of the 25 blades and a double-armed lever coupled with the other blade, means for moving said levers with the blades back into their original position, and means for operating the said levers and the said blades. 30

2. A branch pruning device, comprising, in combination, two oppositely located knife blades movable in opposite directions and subjected to the action of springs adapted to move them into their original position, means guiding said blades, a 35 one-armed lever coupled with one of said blades and a double-armed lever coupled with the other blade, and means for actuating said levers together with the said blades.

3. A branch pruning device, comprising, in combination, two knife blades arranged oppositely to one another, guide members for said blades, a one-armed lever coupled with one of said blades and a double-armed lever coupled with the other blade, a saw-blade connecting the two levers with one 45 another at their free ends, a pulling member attached to one of said levers; and means adapted to counter-act said pulling member.

4. A branch pruning device, comprising, in combination, a frame having pairs of guides located 50 one above the other, knife blades shiftable in said guides in opposite directions, a one-armed lever fulcrumed in said frame and coupled with one of said blades, a double-armed lever likewise fulcrumed in said frame and coupled with the other 55 blade, springs adapted to move said levers back into their initial position, and means for operating the said levers with the blades from below.

FRIEDRICH MAY.
